Primary Examiner — Cynthia M. Chin(74) *Attorney, Agent, or Firm* — Knobbe Martens Olson & Bear, LLP**CLAIM**

The ornamental design for a two wheeled board, as shown and described.

DESCRIPTION

FIG. 1 is a front, top, left-side perspective view of a two wheeled board of our design;

FIG. 2 is a rear, bottom, left-side perspective view thereof;

FIG. 3 is a top view thereof;

FIG. 4 is a bottom view thereof;

FIG. 5 is a front view thereof;

FIG. 6 is a rear view thereof;

FIG. 7 is a left-side view thereof; and,

FIG. 8 is a right-side view thereof.

The broken lines are for the purpose of illustrating portions of the article that form no part of the claim.

UNITED STATES PATENT AND TRADEMARK OFFICE
CERTIFICATE OF CORRECTION

PATENT NO. : D837,322 S
APPLICATION NO. : 29/627176
DATED : January 1, 2019
INVENTOR(S) : Ian Desberg

Page 1 of 1

It is certified that error appears in the above-identified patent and that said Letters Patent is hereby corrected as shown below:

On Page 3, Column 1, Item (56), Line 30, under Other Publications, delete “1/2004 Heinzmann et al.” and insert --3/2004 Kamen et al.--.

On Page 4, Column 2, Item (56), Line 45, under Other Publications, delete “10” and insert --IO--.

Signed and Sealed this
Third Day of March, 2020

Andrei Iancu
Director of the United States Patent and Trademark Office
